TREATMENT OF HYDROCARBONS

Edward Ellisberg, Westfield, N. J., assignor of
three-fourths to Tide Water Oil Company,
Bayonne, N. J., a corporation of New Jersey

Application December 27, 1930, Serial No. 505,027

3 Claims. (Cl. 196—5)

In the well-known Edeleanu process of treating mineral oils with liquid sulfur dioxide to remove constituents which are unstable or are otherwise undesirable, it has been necessary to 5 provide means for continually drying the sulfur dioxide, since the latter takes up any water present in the oil, with the result, were it not for the drying of the sulfur dioxide, that water would accumulate in the system to the detriment of the 10 apparatus besides necessitating interruption of the operation. Special difficulty has been encountered in this respect in the treatment of lubricating oils. In purifying such distillates by the Edeleanu process I have found that it is 15 imperative, or at least necessary in order to avoid heavy expense, that the oil be practically chemically dry. I have, therefore, sought to find a way of making the liquid sulfur dioxide process practical for the treatment of distillates of this 20 description, that is to say, finished or semi-finished oils heavier or more viscous than kerosene and containing no, or substantially no, low-boiling fractions.

Such oils may be expected to contain small 25 fractions of water running up to six-tenths of one percent, 0.4%—0.5% being ordinary. The removal of small residual moisture contents from these hydrocarbon distillates is a special problem. There are various processes for separating 30 the bulk of water from crude oil and the like containing much water, for treating emulsions, and for taking off both water and light hydrocarbon fractions from material on the order of crude oil, but such processes deal with 35 different material than those with which this invention is concerned, and they do not produce a truly dry oil.

In the case of distillates such as motor and other lubricating oils, turbine oils, transformer 40 oils, cable oils and the like, containing residual moisture, or moisture absorbed from the air, the general practice, whenever a fairly dry oil has been required, that is to say one having no more than about 0.4% water or less, has been to heat 45 the oil in a tank by means of steam coils while blowing air through the body of the oil. This operation requires ten to thirty hours of time, the oil is frequently oxidized and injured by the heat and by the action of the air, and the attainment 50 of any exacting degree of dryness is not only difficult but uncertain. The moisture in the air is often sufficient to defeat the operation, and for lubricating oil which should not contain more than about 0.1% moisture when 55 shipped, it is often necessary to defer drying until a day when the atmosphere is sufficiently low in humidity. I appreciate that quicker modes of drying distillates have been proposed, but as far as I am aware they have not been 60 used, or used to any general extent, notwithstanding

the great need for a fast and effective method of drying distillates such as those contemplated in this application. It seems probable, therefore, that such methods either proved to be inefficient or unduly expensive or that they 65 resulted in injury to the distillates, which when finished or partly finished are susceptible of deterioration at temperatures much lower than those at which they were made.

In the present process, lubricating oils and 70 similar materials are dried rapidly to a degree of dryness seldom if ever attained, or attained with any certainty, heretofore, and the oil thus dried is immediately cooled and then treated with liquid sulfur dioxide to remove the undesirable 75 hydrocarbons. The entire process is carried on continuously without at any time heating the oil to a temperature greater than about 200° F.

The accompanying drawing illustrates schematically 80 an apparatus for carrying the invention into effect.

The distillate, which may be of a viscosity ranging from 40 seconds at 100° F., Saybolt Universal, to 150 or 160 seconds at 210° F., Saybolt Universal, 85 and which has a moisture content usually not over 0.6%, is fed by a pump 2 through a line 3 to a heat-exchanger 4, where it is partially heated, as for example to about 130° F. Thence it passes through a connection 5 to a heat-exchanger, or 90 other heater, 6, where it is heated in transit, preferably to about 180° F. to 200° F. 7 is a line for conducting exhaust steam or other heating fluid to the heat-exchanger 6, to bring the temperature of the oil up to the required moderate degree 95 without heating it sufficiently to cause injury, and 8 is a discharge line for the heating fluid or water of condensation.

The heated oil proceeds from the heater 6 through a line 9 to a vacuum chamber 10. This 100 is preferably an upright tower or tank containing baffles 11 over which the oil admitted at 12 flows downward in a shallow stream or film. Upper baffles 13 may be provided for restraining any particles or vapors of the oil which might 105 otherwise escape through the top exit 14 connected with vacuum line 15. Instead of flowing the oil over baffles in the vacuum chamber, it may be attenuated by spraying it into the chamber, it being a desideratum to liberate the water vapor 110 freely from the more or less viscous material without requiring it to struggle through any substantial bulk of oil.

The dried oil is withdrawn from the moderate sized body 16 which collects in the bottom of the 115 vacuumizer, either by gravity if the tank is set high enough, or preferably by a pump 17 which causes the dried oil to flow through a line 18 to the heat-exchanger 4, where it is cooled by exchange with the oil to be treated, preferably to 120

about 140° F. From the heat-exchanger 4 the dried oil passes through a connection 19 to a heat-exchanger, or cooler, 20, where it is cooled by water or other medium (lines 21 and 22) to about 5 100° F. or less, or to such temperature as may be required for further treatment or for shipment.

The more particular purpose of the invention is to prepare the oil for an ensuing liquid-sulfur dioxid treatment, and the line 23 leading the 10 dried oil from the cooler 20 may be understood as being connected with the equipment of the Edeleanu process, such equipment and process being too well known to require illustration and description. The Edeleanu apparatus includes a 15 cooler or coolers for the feed oil and consequently the cooler 20 need not chill the oil to the final temperature required for that treatment.

The water vapor liberated from the oil in the 20 vacuum chamber 10 is withdrawn, and the vacuum is maintained, preferably by a barometric 25 jet condenser 24 connected with the vacuum line 15, this condenser being proportioned and designed to create a vacuum in the chamber upwards of about 26 inches of mercury. A water line 25 supplies water to the body of the condenser, and a steam line 31 supplies steam jets at the top of the condenser and in a branch 26 of the condenser. The water vapor is condensed in the body of the condenser and passes with the 30 water of the top water jet down through the limb 27 of the condenser to a collector 28, from which the water may be conducted through a pipe 29 to a sewer. The non-condensable hydrocarbon vapor or gas present, which might tend to accumulate and adversely affect the vacuum, is entrained 35 by the steam jets in the branch 26 and carried through a line 30 which may connect with the discharge line 29. It will be understood, however, that the barometric condenser illustrated is 40 only one form of means for maintaining the vacuum in the chamber 10, and that any pumping equipment capable of maintaining the requisite vacuum may be used instead.

The employment of a comparatively high vacuum is essential to reduce the temperature which 45 is required to expel the water as vapor from the oil. I have ascertained that it is necessary to heat the oil to a temperature about 40° F. above the theoretical boiling point at the absolute pressure in the chamber, this differential being illustrative since it may be varied for different degrees of vacuum and for different materials. On the other hand the temperature of the oil should not be allowed to go above about 200° F. for the 50 average oil. Temperatures much above that have deleterious effect upon the color, flash-point or lubricating qualities of the oil. Even at these moderate temperatures it is highly desirable that the oil be heated, dried and cooled rapidly. In 55 this process the entire sequence of these operations can be performed in less than one minute, and while so brief a time as that is not intended to be a limitation, it is important to keep the material at a moderate temperature for only a short period.

Within limits on the order of those indicated 60 herein the temperature and vacuum conditions are correlative variable, and they may be varied also in accordance with the particular materials to be treated. For effective and satisfactory results it is desirable that the vacuum be upwards of about 26 inches of mercury. If the

vacuum is not sufficiently high the oil will not be adequately dried even though the temperature be raised to a point at which injury to the oil is likely to result. As a preliminary treatment in the Edeleanu process it is of the greatest importance that these oils be rendered practically chemically dry, so that any moisture remaining is less than about one one-hundredth of one per cent. This is accomplished by the process, as is illustrated by the following example:

A medium motor oil having a viscosity of 300 seconds at 100° F., Saybolt Universal, is dried to 0.005% remaining moisture at a temperature of 180° F. and a vacuum corresponding to 28 inches of mercury.

The invention may be applied to the drying of finished or semi-finished oils refined by different methods, and in such cases the drying may be less thorough.

It will be understood that modifications in the process and in the apparatus are permissible and that the language used in the following claims is intended to cover all the generic and specific novelty of the invention, and all statements of the scope of the invention which as a matter of 100 language might be said to fall between the claims.

I claim:

1. The process of treating lubricating oils or other mineral oil distillates which contain moisture but substantially no low-boiling hydrocarbon fractions, which comprises quickly heating such distillate and subjecting it to a vacuum, the combined conditions of temperature and vacuum being such that the moisture in the oil is eliminated and the oil is dried to below 0.01% moisture without heating the oil at any time to a temperature above about 200° F.

2. The process of treating lubricating oils or other mineral oil distillates which contain moisture but substantially no low-boiling hydrocarbon fractions, which comprises quickly heating such distillate and subjecting it to a vacuum, the combined conditions of temperature and vacuum being such that the moisture in the oil is eliminated and the oil is dried to below 0.01% moisture without heating the oil at any time to a temperature above about 200° F. and quickly cooling the dried oil, the entire operation of heating, drying and cooling each portion of the oil being performed in a period not substantially in excess of one minute, so that the time during which the oil remains heated is as short as possible and no deterioration of the qualities of the oil occurs.

3. The process of removing small fractions of water from lubricating oils or other mineral oil distillates which contain substantially no low-boiling hydrocarbon fractions, which comprises quickly heating such distillate, quickly drying the same by subjecting it to a vacuum not less than about 26 inches of mercury, the temperature to which the oil is heated being about 40° F. or more above the boiling point of water at the vacuum to which the heated oil is subjected but not exceeding about 200° F., the combined conditions of temperature and vacuum being such that the moisture in the oil is eliminated and the oil is dried below 0.01% moisture without heating the oil at any time to a temperature above about 200° F., and quickly cooling the dried distillate.

EDWARD ELLSBERG.
